UNITED STATES PATENT OFFICE.

JOHN T. GREENWOOD, JR., OF BELOIT, WISCONSIN.

FIRE-EXTINGUISHER.

SPECIFICATION forming part of Letters Patent No. 368,085, dated August 9, 1887.

Application filed February 7, 1887. Serial No. 226,824. (No model.)

To all whom it may concern:

Be it known that I, JOHN T. GREENWOOD, Jr., a citizen of the United States, and a resident of Beloit, in the county of Rock and State of Wisconsin, have invented certain new and useful Improvements in Fire-Extinguishers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to portable fire-extinguishers; and it consists in the following improvements, which will be fully understood from the following description, taken in connection with the annexed drawings, in which—

20 Figure 1 is a diametrical section through my improved fire - extinguisher, illustrating my improvements. Fig. 2 is a horizontal section through the device in the plane as illustrated by dotted line $\alpha\alpha$ in Fig. 1.

25 Referring to the annexed drawings by letters, C designates the shell of the device, which is provided with a removable cover, C', adapted to rest upon shoulders C², integral with the said shell. This shell has a number of radial 30 partitions, C³, vertically disposed, which form separate acidulated-water receptacles, C⁴, which will be hereinafter again referred to. These radial partitions terminate at a point, as more fully shown in Fig. 2, so as to allow a space for

35 the cover or casing E to be placed in position against the edges of the said partitions. In the center of the said shell C is suitably suspended a cylinder, A, numerously perforated near its lower end and provided with a vertical

40 partition, d, which extends to a hermetically-sealed cap or cover, C⁴. This cylinder is designed to receive any suitable alkali, which, when mixed with the acidulated water, will produce carbonic-acid gas. External to this

45 cylinder A is another cylinder, B, having a funnel-shaped bottom, e, at the base of which is an annular flange, G, adapted to afford a bearing for a removable casing, E, which, when it is in place, incloses the said cylinder B.

50 At the lower terminus of the funnel of the cylinder B is an extension, which tightly em-

braces the upper end of a vertical pipe, D, which rests by its notched lower end upon the bottom of the shell C, and is provided with two valve-seats, upon which are adapted to play vertically two puppet-valves, a b. Both valves open upwardly and are provided with stop-collars on their lower ends, as shown in Fig. 1.

Surrounding the lower open end of the tube 60 D is a cage, C⁵, to prevent sediment from clogging the lower end of said tube. This cage is preferably hemispherical, and is in communication with the four acidulated-water receptacles C⁴.

65 From the vertical pipe D radiates a pipe, C⁶, which communicates with a vertical cylinder, D, in which is applied a piston, a^x, and a piston-rod, the latter being provided with a packing at the upper end of the cylinder, and also with a handle, as clearly shown in Fig. 1.

Now, in operation, the pump-cylinder D is put in motion and valve a opened by this upward stroke of the piston a^x. This draws a quantity of the acidulated water from the compartment C⁴ of the shell C into the pipes D C⁶ and the pump-cylinder D. The piston a^x is now pressed down, which operation forces the acidulated water through the trap-valve b into the cylinder B, where it mixes with the alkali 80 in cylinder A and rapidly produces carbonic-acid gas. Now, again by depressing the plunger a^x, the carbonated water will be forced through the discharge-pipe c on the fire. The removable cover C' allows free access to the interior of the shell C, and by removing the case E access can be had to the top C⁴ of the alkali-chamber, by removing which this chamber can be readily replenished.

85 In practice common marble-dust may be used in the chamber A, and water containing sulphuric acid may be used in the shell C, the commingling of which produces carbonic-acid gas, which, when mixed and injected on a fire, will extinguish it.

90 Having described my invention, I claim—

1. In a fire-extinguisher, the combination, with the outer casing provided with a removable cover, of radial partitions terminating to afford a space for the insertion of the inner cover, E, subdividing the interior portion of this shell, forming acid-receptacles, a centrally-

arranged perforated alkali-receptacle, a cylinder, B, inclosing this receptacle, provided at its lower end with upwardly-lifting valves, a suitable exhausting and forcing pump communicating with a pipe, D, between said valves, and an ejecting-pipe leading from the lower part of the said cylinder outward, substantially as described.

2. The combination, in a fire-extinguisher, of a casing provided with a removable cover and radial partitions, an alkali-chamber perforated near its lower part and provided with a vertical partition, a cylinder external to said chamber provided with upwardly-lifting trap-valves, a strainer below these valves, an ejecting-pipe above the valves, and a suction and forcing pump, substantially as described.

3. The combination, in a fire-extinguisher, of the following instrumentalities, to wit: a casing provided with radial partitions and a removable cover, an alkali-cylinder hermetically sealed on top, a cylinder, B, external thereto, provided with valves, an ejecting-pipe and a pump, and a removable case, E, all substantially as described.

25 In testimony whereof I affix my signature in presence of two witnesses.

JOHN T. GREENWOOD, JR.

Witnesses:

JOHN MARTIN,
FRANK GREENWOOD.
